UNITED STATES PATENT OFFICE

2,249,813

CIRCUIT BREAKER

Lloyd W. Dyer, Swissvale, Pa., assignor to Westinghouse Electric & Manufacturing Company, East Pittsburgh, Pa., a corporation of Pennsylvania

Application November 7, 1936, Serial No. 109,720

17 Claims. (Cl. 175—294)

My invention relates generally to electrical apparatus and more particularly to circuit breakers for opening and closing power circuits.

The principal object of my invention is to provide an improved automatic reclosing circuit breaker structure which is entirely self-contained, and operated without the use of any external source of electrical energy other than that derived from the circuit which it controls.

A further object of my invention is to provide an improved, self-contained automatic reclosing circuit breaker which is simple and efficient in operation, of rugged construction, and which may be readily and economically manufactured and installed.

A further object of my invention is to provide an improved circuit breaker embodying a novel control arrangement for opening the contact means of the breaker in response to abnormal circuit conditions and for automatically reclosing the contact means after an opening operation.

A further object of my invention is to provide an improved circuit breaker embodying a novel control means for opening the contacts of the breaker in response to abnormal circuit condition and for automatically reclosing the same, and in which a novel means is provided for locking the contact means in open circuit position when a predetermined number of successive opening and closing operations of the contact means occur within a predetermined time interval.

A further object of my invention is to provide a novel control means for a circuit breaker for opening the contact means of the breaker in response to abnormal circuit conditions and for automatically reclosing the same which does not require any external electrical energy other than that derived from the circuit controlled by the breaker.

The principal field for immediate application of my invention is in connection with rural power distribution systems where it is economically impractical to install the auxiliary control networks and apparatus for controlling circuit breakers such as are used in the more thickly populated sections. For such rural systems, it is particularly desirable to have low cost automatic reclosing protective circuit breaker structures which are self-contained and operated without external auxiliary electric energy and which will lock open in response to a predetermined number of successive reclosures occurring within a predetermined period of time. My improved circuit breaker provides a particularly

desirable structure for meeting the requirements of such application. While my invention is particularly suitable for such use, it is obvious that it is equally applicable to various other types of installations or uses.

The novel features that I consider characteristic of my invention are set forth in particular in the appended claims. The invention, itself, however, both as to structure and operation, together with additional objects and advantages thereof, will best be understood from the following detailed description of a specific embodiment thereof when read in connection with the accompanying drawing in which:

15 Figure 1 is a vertical sectional view of my improved circuit breaker, and

Fig. 2 is an enlarged elevational view of the mechanical lock-out device and retarding means embodied in the circuit breaker shown in Fig. 1, 20 a part of the side wall of the device being broken away in order to illustrate certain features of the device.

Referring to Fig. 1 of the drawing, the various parts and operating mechanisms of the circuit breaker are mounted within a metal tank 5. The opposite end walls of the tank each have formed integral therewith a flange 7 which extends outwardly at right angles therefrom. A metal cover 9 is removably mounted on the top 25 of the tank by any suitable form of removable fastening means. Each of the flanges 7 of the tank 5 is provided with an opening 11 and an aligned depending metal sleeve 13 in which is inserted a porcelain lead-in bushing 14 for the conductor wires which connect the breaker in its 30 external circuit. The enclosure formed by the tank 5 and cover 9 is adapted to be mounted on a transmission pole or other form of power line support, and the metal sleeves 13 prevent the 35 entrance of rain and moisture into the interior of the enclosure.

The contact means of the circuit breaker comprises a stationary contact 15, a movable contact 17, and an arc extinguishing means indicated 45 generally at 19. The arc extinguishing means is not an important part of my invention, and any suitable structure may be used. The contact means and arc extinguishing means are immersed in a body of oil 21 contained in the 50 tank 5.

The movable contact 17 is secured to a switch member 23 which consists of a rod mounted for vertical movement within the tank by any suitable form of guide means. The switch member 55 is movable upwardly to an open circuit position

to open the contact means and is biased by gravity or a spring downwardly to a closed circuit position to cause the movable contact to engage the stationary contact.

The upper end of the switch member has associated therewith a mechanical device indicated generally at 24 for controlling the downward or closing movement of the switch member 23. The device 24 comprises in general, a retarding mechanism including a gear 25 for engaging rack teeth 27 formed on the switch member 23, and a counting lock-out device indicated generally at 29 (Fig. 2). The retarding device including the gear 25 permits free upward or opening movement of the switch member 23 but retards the downward or closing movement of said member. Any suitable type of retarding means such as an escapement or dash-pot device may be used for this purpose. The counting lock-out mechanism 29 which will be hereinafter described in connection with Fig. 2 operates to lock the switch member 23 in the open circuit position whenever a predetermined successive number of circuit interrupting operations occur within a predetermined period of time. The retarding means and the counting lock-out mechanism 29 are mounted in a suitable casing 31 supported within the tank 5.

The control arrangement for operating the switch member comprises, in general, an operating member 33, an operating electromagnet means 35 for moving the operating member 33 to effect movement of the switch member 23 to open circuit position, a holding electromagnetic means 37 acting in opposition to the operating means 35 for normally holding the operating member 33 against movement by the operating means, and an electro-responsive means 39 for rendering the holding means 37 ineffective to hold the operating member against movement by the operating means in response to predetermined circuit conditions.

The operating member 33 comprises a rod 38 provided with a slot 41 at the lower end thereof and an angular extension 43 at the top. The operating member 33 is mounted for vertical movement within the tank by any suitable form of guiding means between a normal position, as shown in Fig. 1, and an operative position. The operating member 33 is coupled to the movable switch member 23 by means of a link 45 pivoted at one end to a fixed pin 47 and pivotally connected to the switch member at its opposite end by a pin and slot connection 49. The link 45 carries a pin 51 which engages in the slot 41 of the operating member 33. This form of loose coupling between the operating member 33 and the switch member 23 permits the operating member to gain momentum before it begins to move the switch member so as to provide for a rapid opening of the contact means. The coupling means also permits movement of the switch member 23 by some other independent form of conventional operating mechanism, not shown, so that the switch member 23 may be moved to open and closed circuit position independently of the control arrangement previously described if desired. The operating electromagnet 35 consists of a stationary core 53, an operating winding or coil 55, and a moving core 57. The moving core 57 is connected at one end by a rod 59 to the angular extension 43 of the operating member 33, and at its lower end by a rod 61 to the armature 63 of the holding electromagnetic means 37.

The holding electromagnetic means comprises a stationary core 65, a holding coil 67, a short circuiting control coil 69, and the movable armature 63. The operating coil 55 and core 57, when energized, exert a force tending to move the operating member to its upper or operative position. The holding coil 67, however, produces an opposite force on the operating member 33 by means of the armature 63, which is sufficient normally to hold the operating member in its normal position against movement by the operating means 35, so that the contacts normally remain in closed circuit position as shown in Fig. 1. The circuit for the winding of the short circuiting coil 69 is normally open at the contacts 71 of the electro-responsive means 39. When the contact means 71 are closed by the electro-responsive means 39, the circuit of the short circuiting winding 69 is short-circuited and acts to counteract the holding force of the holding coil 67, so that the holding coil is no longer able to restrain the operating member 33 against movement to its operative position by the operating means 35. Under such conditions the operating member is moved to its operating position by the force exerted by the coil 55 and the core 57 to move the movable switch member 23 to its open circuited position.

The electro-responsive means 39 comprises a stationary core 73, a pivoted armature 75, the contact means 71 and a control coil 76. The armature 75 is biased away from the pole face of stationary core 73 by any suitable means such as a spring 77. The operating characteristics of the electro-responsive means are such that under normal current conditions of the circuit controlled by the breaker the magneto-motive force developed is insufficient to attract the armature 75 to close the contacts 71. However, under abnormal current conditions such as overload or short-circuit the magneto-motive force developed is increased sufficiently to attract the armature 75 and close the contact means 71 to short circuit the control coil 69.

The trip characteristic of the electro-responsive control means 39 may be adjusted in any well known manner as, for example, by changing the normal tension of the biasing spring 77 which biases the armature 75 away from the core 73, or by changing the normal air gap between the armature 75 and core 73. Thus the control means 39 may be adjusted to respond to different values of overload current.

The circuit for the breaker extends from a line conductor 78 through the control coil 76 of the electro-responsive means 39, a conductor 81, the operating coil 55 of the electro-magnetic operating means 35, a conductor 83 through the holding coil 67, through a flexible shunt conductor 85 to the movable switch member 23, movable contact 17 and stationary contact 15, to a load conductor 87.

The operation of the apparatus as thus far described is as follows: The contact means comprising the contacts 15 and 17 is normally closed and the coils 76, 55 and 67 thus normally energized since they are in series circuit with the contact means. The force exerted by the operating means 35 exerts a force on the movable operating member 33 tending to move the same to its operative position to cause separation of the contacts 15 and 17. The holding coil 67, however, exerts an opposite force on the operating member 33 such as to normally hold the operating member in its normal position against move-

ment by the operating means 35 so that the contacts remain in their closed circuit position. If an overload of sufficient magnitude occurs in the circuit controlled by the breaker, the contacts 71 of the electro-responsive means 39 are closed to short circuit the winding of the control coil 69. The short circuiting of this winding counteracts the holding force exerted by the holding coil 67 so that the operating member 33 is no longer restrained by the holding coil. The electromagnetic operating means 35 then functions to move the operating member 33 to its operative position. This movement of the operating member 33 is transmitted by the link 45 to the movable switch member 23 and moves the latter to open circuit position to interrupt the circuit. The interruption of the circuit controlled by the breaker deenergizes the windings 55, 67, and 76, so that the movable switch member is permitted to return to closed circuit position by gravity or spring bias. The downward or closing movement of the movable switch member is retarded by the retarding means 25, so that the circuit remains open for a predetermined period of time. When the movable switch contact reaches its closed circuit condition, the coils 55 and 67 and 76 are again energized by the circuit controlled by the breaker and if the overload condition still exists, the opening operation is repeated as described above. If, during the open condition of the circuit breaker, the overload condition has ceased, the breaker remains in closed circuit position after the contacts have closed, by reason of the fact that the holding coil 67 normally prevents movement of the operating member 33.

As has been pointed out previously, if the overload condition persists, the contact means of the circuit breaker would ordinarily be opened and automatically reclosed as long as the condition exists. It is desirable, therefore, that some means be provided to limit the number of reclosures of the circuit breaker under a continuous overload condition. The means for thus limiting the number of reclosures of the circuit breaker is the counting lock-out device 29. The counting lock-out device 29 includes a disk 89 pivotally mounted on a pin or shaft 91. The disk 89 is biased in a counter-clockwise direction by means of a return spring 93 connected at one end to a pin 95 carried by the disk 89 and its other end to a pin 97 secured to a wall of the casing 31. The disk 89 also carries a plurality of pins 99, 101 and 103, as shown in Fig. 2. The upper end of the movable switch member 23 has a recess 105 formed therein in which is pivotally mounted a latch 107. The latch is biased outwardly by a resilient steel spring 109 secured to the switch member 23 by means of a screw 111. The upper face of the latch normally engages the pin 99 as shown in Fig. 2. A pair of locking pins 113 and 115 extend outwardly from one face of the disk and are so positioned that when the disk 89 is rotated a predetermined distance in the clockwise direction, the pin 113 moves to the position 113' where it is engaged and held by latch 117, and the pin 115 moves to a position beneath the lower face 131 of the latch 107, to lock the switch member in open circuit position when a predetermined number of successive opening and closing operations have occurred in a predetermined period of time.

The latch 117 is biased to latching position by a spring 119. The latch 117 may be moved about its pivot pin 121 to releasing position to release the pin 113 by means of a manual oper-

ating handle 123, to allow the switch member to return to its closed circuit position after it has been locked open as will hereinafter be described.

The counter-clockwise rotation of the disk 89 is retarded by means of a dash pot device 125 pivotally connected to a stationary pin 127 carried by the casing 31 and to the disk 89 by means of a pin 129.

The operation of the counting lock-out device 10 is as follows: When the switch member 23 moves to the open circuit position, the latch 107 moves the pin 99 to the position 99' thus partially rotating the disk 89. After the circuit has been interrupted the switch member 23 returns slowly to closed circuit position being retarded by the retarding means 25. The disk 89, however, is retarded to a greater extent by the dash pot 125 than the switch member is by the retarding means 25 so that the pin 99 remains in the position 99' for a predetermined period of time after the contacts close. If the overload condition which causes separation of the contacts is of a transitory nature so that it ceases to exist by the time the contact means 15 and 17 have closed 15 the switch member remains in closed circuit position and the disk 89 rotates very slowly in the counterclockwise direction under the influence of the return spring 93, back to its normal position shown in Fig. 2, so that the pin 99 is returned from the position 99' to the position shown in the full lines in Fig. 2. The disk 89 is thus partially rotated each time the circuit breaker switch member 23 moves to the open 20 circuit position and if the opening operations 30 are discontinuous or occur at infrequent intervals the disk 89 is returned each time to normal position. However, if a continuous overload occurs the switch member 23 in its first opening operation moves the pin 99 to the position 99' and then returns to closed circuit position. Immediately that it reaches the closed circuit position, it is again moved to the open circuit position by the control apparatus, since the overload condition still exists. The switch member is moved 40 to the open circuit position the second time before the disk 89 has returned to normal position, and in its second opening movement, the latch 107 of the switch member 23 engages the second pin 101 and imparts a further rotation to the disk 89. The switch member again returns to closed circuit position, and when it moves to the open circuit position for the third time, it engages the pin 103 to impart a further rotational movement to the disk 89. At this time the pin 50 113 has been rotated a sufficient distance to be engaged by the latch 117 so that the disk is locked against return movement to its normal position. When the pin 113 is in the position 113' in which it is latched by the latch 117, the pin 115 is in a position in which it engages the undersurface 131 of the latch 107, so that the switch operating member 23 is locked in the open circuit position. The switch member 23 cannot be moved to closed circuit position until the operating handle 60 65 70 75 123 has been moved to release the latch 117 from its engagement with the pin 113.

It will thus be seen that as long as the opening and closing operations of the switch member 23 occur at infrequent intervals, the disk 89 has no effect thereon and merely returns after each operation to its normal position, but if the switch member moves to open circuit position three successive times within a predetermined period of time fixed by the adjustment of the dash pot 125,

it will be locked in the third and final open circuit position by means of the pin 115.

If a fast reclosure is desired the retarding means 25 may be omitted so that the switch member can move freely to closed circuit position under the influence of gravity or spring bias.

While I have shown one specific embodiment of my invention, it is obvious that various changes may be made in the structure without departing from the spirit of the invention.

It will be seen that I have provided an improved automatic reclosing protective circuit breaker structure which is entirely self-contained and is operated without the use of any external auxiliary source of electrical energy. The circuit breaker operates to adequately protect the circuit in which it is connected by opening the circuit in response to an overload condition and automatically reclosing the same after a predetermined time, and if the overload is of a more or less permanent nature, the circuit breaker, after a predetermined number of operations, is locked in the open circuit position and cannot be reclosed except by removing the cover and moving the handle 123 to release the latch means 117.

While, in accordance with the patent statutes, I have given the foregoing details of a practical embodiment of my invention, it is to be understood that many of these are merely illustrative and that variations in their precise form will be desirable in some applications. I desire, therefore, that the language of the accompanying claims be accorded the broadest reasonable construction and that my invention be limited only by the language of the claims and by what is shown in the prior art.

I claim as my invention:

1. An automatic reclosing power circuit breaker comprising a pair of contacts biased to closed position, an operating member movable to open said contacts, electrical means connected in the circuit in series with said contacts acting on said operating member to move the same to open said contacts, means normally preventing movement of said member by said first means, and means operable in response to predetermined conditions in the circuit of said contacts for rendering said second means ineffective to prevent opening movement of said operating member, said condition responsive means being operable as aforesaid free of any restraint resulting from the force of said first means.

2. An automatic reclosing circuit breaker comprising, a pair of contacts biased to closed position, an operating member movable to open said contacts, a first electrically energized means acting on said operating member to move the same to open said contacts, a second electrically energized means acting on said member in opposition to said first means for normally preventing movement of said member, and control means for rendering said second electrically energized means ineffective to prevent movement of said operating member by said first means, said first and second means being connected in circuit with said contact means.

3. An automatic reclosing circuit breaker comprising, contact means movable to an open and to a closed circuit position and biased to the closed circuit position, the combination of an operating member coupled to said contact means movable from a normal position to a second position to move said contact means to the open circuit position, a first electrically energized means connected in circuit with said contact

means acting to move said member to said second position, a second electrically energized means connected in circuit with said contact means acting on said member in opposition to said first means to normally hold said member in said normal position and means responsive to predetermined conditions for rendering said second means ineffective to prevent movement of said member by said first means.

4. An automatic reclosing circuit breaker comprising in combination, contact means having an open and a closed circuit position, said contact means being biased to the closed circuit position, an operating member coupled to said contact means movable from a normal position to a second position to open said contact means, electrically energized means comprising an operating coil acting to move said member to said second position and a holding coil acting on said member in opposition to said operating coil for normally holding said member in said normal position, both said coils being connected in circuit with said contact means, means connected in circuit with said contact means responsive to predetermined conditions for rendering said holding coil ineffective to hold said member from moving to said second position to open said contact means, the separation of said contact means effecting deenergization of said coils and condition responsive means to permit said contact means to reclose.

5. An automatic reclosing circuit breaker comprising in combination, contact means having an open and a closed circuit position, said contact means being biased to the closed circuit position, an operating member coupled to said contact means movable from a normal position to a second position to open said contact means, electromagnetic means comprising an operating coil acting to move said member to said second position and a holding coil acting on said member in opposition to said operating coil for normally holding said member in said normal position, both said coils being connected in circuit with said contact means, means connected in circuit with said contact means responsive to predetermined conditions for rendering said holding coil ineffective to hold said member from moving to said second position to open said contact means, the separation of said contact means effecting deenergization of said coils and said condition responsive means to permit said contact means to reclose.

6. In an oil circuit breaker having a casing for enclosing oil immersed relatively movable contact means biased to the closed circuit position, the combination of control apparatus mounted in said casing for opening and reclosing said contact means comprising means including an operating coil for moving said contact means to the open circuit position, a holding coil acting in opposition to said operating coil to prevent movement of said contact means to the open circuit position by said operating coil, said coils being connected in circuit with said contact means, and means operable in response to predetermined conditions in the circuit for rendering said holding coil ineffective to prevent opening of said contact means by said operating coil.

7. An automatic reclosing circuit breaker comprising a stationary contact, a movable contact biased to closed circuit position to engage said stationary contact and movable to an open circuit position, means retarding the movement of said movable contact to closed circuit position, an

operating member coupled to said movable contact movable from a normal position to a second position to move said movable contact to the open circuit position, electrically energized means including an operating coil connected in circuit with said contacts for moving said member to said second position and a holding coil connected in circuit with said contact means acting to prevent movement of said member by said operating coil, and means responsive to predetermined conditions in the circuit for rendering said second coil ineffective to prevent movement of said member.

8. A self-contained automatic oil circuit breaker comprising a stationary contact, a movable contact biased to closed circuit position to engage said stationary contact and movable to an open circuit position, means retarding the movement of said movable contact to closed circuit position, an operating member coupled to said movable contact movable from a normal position to a second position to move said movable contact to the open circuit position, electrically energized means including an operating coil connected in circuit with said contacts for moving said member to said second position and a holding coil connected in circuit with said contact means for preventing movement of said member by said operating coil, and means responsive to predetermined conditions in the circuit for rendering said second coil ineffective to prevent movement of said member, and a casing for enclosing said elements having a body of oil therein for covering said contacts.

9. An automatic reclosing circuit breaker comprising relatively movable contact means biased to closed circuit position and movable to open circuit position, the combination of an operating member coupled to said contact means movable from a normal position to a second position to move said contact means to the open circuit position, said member in its normal position permitting relative movement of said contact means, electro-magnetic means including an operating coil for exerting a force on said member to move the same to said second position and a holding coil for exerting a force on said member in opposition to the force exerted by said operating coil for normally holding said member in said normal position, said coils being connected in circuit with said contact means, means responsive to predetermined conditions in the circuit controlled by said contact means for so reducing the force exerted by said holding coil that said member is moved to said second position by said operating coil to open said contact means.

10. In a circuit breaker having relatively movable contact means biased to closed circuit position and movable to open circuit position, the combination of an operating member coupled to said contact means movable from a normal position to an operative position to move said contact means to the open circuit position, means including a first coil for normally exerting a force on said member to move the same to its operative position and a second coil for normally preventing movement of said member by said first coil, said coils being connected in circuit with said contact means, means operable in response to predetermined conditions in the circuit to render said second coil ineffective to prevent movement of said member by said first coil, said coils and means being deenergized when said contact means has moved to the open circuit

position to permit said contact means to return to the closed circuit position.

11. In a circuit breaker having relatively movable contact means biased to closed circuit position and movable to open circuit position, the combination of an operating member coupled to said contact means movable from a normal position to an operative position to move said contact means to the open circuit position, electro-magnetic means including a first coil for exerting a force on said member to move the same to its operative position and a second coil for exerting an opposite force on said member to normally prevent movement of said member by said first coil, said coils being connected in circuit with said contact means, means operable in response to predetermined conditions in the circuit for rendering said second coil ineffective to prevent movement of said member by said first coil, said coils and means being deenergized when said contact means has moved to the open circuit position to permit said contact means to return to the closed circuit position, and means for retarding the movement of said contact means to the closed circuit position.

12. In a circuit breaker having relatively movable contact means biased to closed circuit position and movable to open circuit position, the combination of an operating member coupled to said contact means movable from a normal position to an operative position to move said contact means to the open circuit position, electrically energized means including a first coil for exerting a force on said member to move the same to its operative position and a second coil for exerting an opposite force on said member to normally prevent movement of said member by said first coil, said coils being connected in circuit with said contact means, an electro-responsive means connected in circuit with said contact means operable in response to a predetermined condition to render said second coil ineffective to prevent movement of said member by said first coil, said coils and electro-responsive means being deenergized when said contact means has moved to the open circuit position to permit said contact means to return to the closed circuit position, means for retarding movement of said contact means to the closed circuit position.

13. In a circuit interrupting device having relatively movable contact means biased to closed circuit position and movable to open circuit position, the combination of an operating member coupled to said contact means having a normal position permitting relative movement of said contact means and movable to an operative position to move said contact means to the open circuit position, electro-magnetic means including an operating coil for exerting a force on said member to move it to said operative position and a second coil for exerting an opposite force on said member for normally holding said member against movement from its normal position by said operating coil, said coils being connected in circuit with said contact means, means operable in response to predetermined conditions in the circuit for rendering said second coil ineffective to prevent movement of said member by said operating coil, said coils and means being deenergized when said contact means opens the circuit to permit said contact means to return to closed circuit position.

14. In a circuit interrupting device having relatively movable contact means biased to closed

circuit position and movable to open circuit position, the combination of an operating member coupled to said contact means having a normal position permitting relative movement of said contact means and movable to an operative position to move said contact means to the open circuit position, electrically energized means including an operating coil for exerting a force on said member to move it to said operative position, a second means for holding said member against movement from its normal position by said operating coil, said coil being connected in circuit with said contact means, means operable in response to predetermined conditions in the circuit for rendering said second means ineffective to prevent movement of said member by said operating coil, said coil and means being deenergized when said contact means opens the circuit to permit said contact means to return to closed circuit position, and means for retarding movement of said contact means to closed circuit position.

15. In an automatic reclosing circuit breaker relatively movable contact means movable to an open and to a closed circuit position, means biasing the contact means to closed circuit position, the combination of an operating member coupled to said contact means movable from a normal position to an operative position to move said contact means to open circuit position, electromagnetic means including an operating coil for exerting a force on said member to move it to said second position, a second coil for exerting an opposite force on said member to normally prevent movement thereof by said operating coil, said coils being connected in circuit with said contact means, and a third coil having a normally open control circuit, electro-responsive means connected in circuit with said contact means operable in response to predeter- 40

mined conditions for closing the control circuit of said third coil to reduce the force exerted by said second coil a sufficient amount to allow said operating coil to move said member to its operative position.

16. In a self-contained automatic reclosing circuit breaker, a stationary contact, a cooperating movable contact biased to closed circuit position, an operating member coupled to said movable contact movable from a normal position to a second position to move said movable contact to open circuit position, electrically energized means including an operating coil connected in circuit with said contacts acting to move said operating member to its second position, a holding coil connected in circuit with said contacts for normally preventing movement of the operating member by said operating coil, means operable in response to predetermined conditions in the circuit for rendering said holding coil ineffective to prevent movement of said operating member by said operating coil, and means retarding closing movement of said movable contact, and a casing for enclosing all of the above-mentioned means and elements.

17. In a self-contained automatic reclosing circuit breaker, a pair of relatively movable contacts biased to closed circuit position, operating means for said contacts including a first electromagnet connected in circuit with said contacts acting to open said contacts, a second electromagnet connected in circuit with said contacts for normally preventing opening of said contacts by said first electromagnet, means operable in response to predetermined conditions in the circuit for rendering said second electromagnet ineffective to prevent opening of said contacts by said first electromagnet, and means retarding closing of said contacts.

LLOYD W. DYER.
